REFRIGERATION CONTROL APPARATUS

William L. McGrath, St. Paul, Minn., assignor to
Minneapolis-Honeywell Regulator Company,
Minneapolis, Minn., a corporation of Delaware

Application April 14, 1939, Serial No. 267,807

6 Claims. (Cl. 62—4)

This invention relates to refrigeration and more particularly to automatic controls therefor.

The primary object of this invention is to provide an automatic control arrangement for a refrigeration system having a variable capacity compressor or other type of actuating means, this arrangement acting to vary the capacity in steps, and being readily adjustable so that cut-in and cut-out points of the various capacity steps can be independently adjusted.

A further object of this invention is the provision of a control arrangement of this type in which the adjusting means is arranged so that adjustment may be made over a wide control range, but which prevents adjustment which would provide an improper control sequence.

Other objects will appear from the following description and the appended claims.

For a full disclosure of this invention, reference is made to the following detailed description and to the accompanying drawing in which:

Figure 1 illustrates diagrammatically a refrigeration system having a two-speed compressor controlled in accordance with this invention;

Figure 2 is an elevation, partly in section, of the suction pressure refrigeration controller utilized;

Figure 3 is a side sectional elevation taken on line 3—3 of Figure 2, and

Figure 4 is an elevation of the exterior of the instrument.

Referring to Figure 1, reference character 1 indicates a space to be refrigerated. Within this space may be located an evaporator coil 2 which is separated from the space by a baffle 3. A fan 4 may be provided for forcing circulation of air from the space over the evaporator coil 2, and this fan may be controlled by a thermostat 5. This thermostat may either stop or start the fan 4 or modulate its speed in a manner to maintain the desired space temperature.

The evaporator coil 2 forms a part of a refrigeration system having a compressor 6 which is driven by a two-speed electric motor 7. The discharge of the compressor 6 is connected by a pipe 8 to the usual condenser coil 9 which in turn is connected to a receiver 10. This receiver is connected by a liquid line 11 to an expansion valve 11a at the inlet of evaporator coil 2. The outlet of this evaporator coil 2 is connected by a suction line 12 to the inlet of the compressor 6. This system functions in the usual manner to condense refrigerant in the condenser 9 and to evaporate it within the evaporator 2

thereby causing the evaporator to become chilled.

The electric motor 7 is of the two-speed type and is provided with terminals 13, 14, and 15. The terminal 13 is connected to a line wire 13a. If power is supplied to the motor 7 through terminal 14, this motor will operate at low speed, while if power is supplied to the motor through terminal 15, this motor will operate at high speed. The terminal 14 is therefore a low speed terminal and the terminal 15 is a high speed terminal.

The operation of the motor 7 is controlled by a pair of relays 16 and 17. The relay 16 includes a pull-in coil 18 which actuates through an armature 19 a pair of switch arms 20 and 21 which cooperate with contacts 22 and 23, respectively. When the pull-in coil 18 is energized, the armature 19 causes switch arms 20 and 21 to be brought into engagement with their respective contacts. However, when the coil 18 is deenergized, the switch arms 20 and 21 are disengaged from these contacts by the action of gravity or springs, not shown. The relay 17 is similar to relay 16 and includes a pull-in coil 24 which actuates switch arms 25 and 26. The switch arm 25 cooperates with contacts 27 and 28 while the switch arm 26 cooperates with contact 29.

The line wire 30 is connected to the switch arm 20 of relay 16 and the contact 22 of this relay is connected by wire 31 to the switch arm 30 25 of relay 17. The contact 27 of this relay is connected to the low speed terminal 14 of motor 7 by wire 32, and the contact 28 is connected to the high speed terminal 15 by wire 33. It will be apparent that when relay 16 is deenergized, 35 no power can be transmitted to either terminal 14 or 15 due to the switch arm 20 disengaging contact 22. However, when the relay 16 is energized power will then be transmitted to either terminal 14 or 15 of motor 7, depending upon 40 the position of switch arm 25 of relay 17. If this relay is deenergized, the switch arm 25 engages contact 27 thus completing the power circuit to the low speed terminal 14 for operating the compressor at low speed. Conversely, if relay 17 is 45 energized, the switch arm 25 engages contact 28 for completing the power circuit through terminal 15 thereby operating the compressor at high speed. The relay 16 therefore determines whether or not the compressor shall operate, and the relay 17 determines at what speed the compressor shall operate.

The relays 16 and 17 are controlled by means of a suction pressure controller 35. This controller includes a Bourdon tube 36 which is connect-

ed to the suction line 12 by means of a pipe 31. Referring now to Figures 2, 3, and 4, the Bourdon tube 36 is suitably secured to a casing 38 and rotates a collar 39 which is secured to a shaft 40. 5 This shaft is rotatably mounted in a hollow boss 41 in the back of the instrument housing and in a pacer 42 which is secured to the housing 38 by means of a screw 43. It will be apparent that 10 change in suction pressure will cause the Bourdon tube 36 to rotate the shaft 40. Thus an increase in suction pressure will cause rotation of this shaft in a clockwise direction as viewed in Figure 2, while a decrease in suction pressure will cause rotation of this shaft in the opposite direction. 15 Mounted upon the shaft 40 by means of a collar 44 is a pointer 45 which extends upwardly and outwardly to the front face of the casing 38 from which it may be observed through a slot 46 (Figure 4). 20 Rotatably mounted upon the spacer 43 are arms 47, 48, 49, and 50. The arm 48 carries an insulation member 51 which carries a pair of contacts 52 and 53. Attached to the arm 48 is a forwardly extending arm or extension 55 which extends through a slot 56 in the instrument cover (Figure 4) and which is provided with a pointer 57. It will be apparent that by shifting the point 57 along the slot 56, the angular position of the arm 48 and hence the position contacts 52 and 30 53 may be adjusted. The arm 47 carries an insulation member 58 which in turn carries contacts 59 and 60. The arm 47 is also provided with an extension 61 which also extends through the slot 56 and is provided with a pointer 62. The 35 arm 49 carries an insulation member 63, supporting contacts 64 and 65 and is connected to an extension or pointer 66 which extends through the slot 67 in the front of the instrument cover. Similarly, the arm 50 supports an insulation member 68 carrying contacts 69 and 70. This arm is also provided with a pointer 71 extending through the slot 67. It will be apparent that by 40 adjusting the positions of the pointers 57, 62, 66, and 71, the positions of the various sets of contacts may be readily and independently adjusted.

Mounted upon the shaft 40 by means of collars 75, 76, 77, and 78 are contact arms 79, 80, 81, and 82, respectively. The contact arm 79 carries a 50 contact member 83 which is adapted to bridge contacts 59 and 60. Similarly, the contact arm 80 carries a contact member 84 which is adapted to bridge the contacts 52 and 53. The contact arms 81 and 82 are provided with offset portions 55 as indicated at 85 for permitting these arms to clear the arms 47 and 48. These contact arms 81 and 82 also carry contact members 86 and 87. Located within each of the hubs or collars 75, 76, 77, and 78 is a spring 88 which is arranged 60 so as to force the arms 79, 80, 81, and 82 into contact with a stop member 90 attached to the arm 45. This stop member maintains the various contact arms in alignment. It will be apparent that upon increase in suction pressure from a 65 minimum value, the shaft 40 will be rotated in a clockwise direction as seen in Figure 2 thereby rotating the contact arms 79, 80, 81, and 82 in this direction. With the various pointers adjusted as indicated, the contact member 84 will 70 first engage contacts 52 and 53 thereby bridging these contacts. Upon increase in suction pressure, the shaft 40 will be rotated further, this action being permitted by the spring or a strain release connection between the shaft 40 and the hub 75. It will be apparent that as the suction

pressure increases the contact member 86 will bridge contacts 69 and 70, the contact member 83 will bridge contacts 59 and 60, and the contact member 87 will bridge the contacts 64 and 65 in the order stated. By adjusting the pointers 57, 62, 66, and 71, the values of suction pressure at which the various pairs of contacts are bridged and unbridged can be readily and independently adjusted. 5

Referring again to Figure 1, the various contacts and contact members are shown displaced from their normal positions in order to appear in this diagrammatic figure. Assuming that the suction pressure rises to a value causing the contact member 83 to bridge contacts 59 and 60, the coil 18 of relay 16 will be energized as follows: transformer secondary 93 of step-down transformer 94, wire 95, wire 96, contact 59, contact member 83, contact 60, wire 97, pull-in coil 18 and wire 98 to secondary 93. This will cause 20 switch arms 20 and 21 to engage their respective contacts. Engagement of switch arm 20 with contact 22 will complete a circuit to the switch arm 25 of relay 17, and as this relay is now de-energized the power circuit to the motor 17 will be completed through the low speed terminal 14, thereby causing operation of the compressor at low speed. Engagement of switch arm 21 with contact 23 will complete a maintaining circuit for coil 18 which is independent of contacts 59 and 60. This circuit is as follows: secondary 93, wire 95, wire 99, contact 52, member 84, contact 53, wire 100, switch arm 21, contact 23, coil 18, and wire 98 to secondary 93. Due to this holding circuit, the relay 16 will remain energized even though the contact member 83 disengages contacts 59 and 60 upon falling suction pressure. The compressor will therefore remain in operation until the suction pressure falls to a point sufficient to cause the contact member 84 to disengage contacts 52 and 53. The arrangement just described therefore places the compressor into operation when the suction pressure rises to a predetermined high value and maintains the compressor in operation until the suction pressure falls to a predetermined lower value. By adjusting the pointer 62, the cut-in value may be varied to whatever value is desired and by adjusting the pointer 57, the cut-out point for the compressor may be likewise adjusted. Due to the pointers 57 and 62 being located in a common slot, it is impossible to adjust the device to reverse the relative positions of the various contacts. This prevents the device from being adjusted in a manner which would render it inoperative to obtain proper control sequence. 45 50 55

In the event that the load upon the evaporator 2 is such that it cannot be carried by operation of the compressor at low speed, the suction pressure will increase to a point wherein the contact member 87 bridges contacts 64 and 65. At this time the contact member 86 will have bridged contacts 69 and 70. Due to bridging of the contacts 64 and 65, the coil 24 of relay 17 will be energized as follows: secondary 93, wire 95, wire 88, contact 65, member 87, contact 64, wire 101, coil 24, and wires 102 and 98 to secondary 93. This will cause the switch arm 25 of this relay to engage contact 28 which will cause the compressor motor 7 to operate at high speed. Due to 70 engagement of switch arm 26 with contact 28, a holding circuit for coil 24 will be established through contacts 68 and 70 as follows: transformer secondary 93, wire 95, wire 98, wire 103, contact 68, member 88, contact 70, wire 104, 75

switch arm 26, contact 29, coil 24, and wires 102 and 98 to secondary 93. This will maintain the compressor in operation until the suction pressure falls to a value at which the contact member 86 disengages contacts 69 and 70. As indicated in Figure 1, the position of contacts 69 and 70 may be adjusted so that the cut-out point for relay 17 is close to the cut-out point of the relay 16. Thus when the compressor is placed into operation at high speed, it will continue to operate at this high speed until the suction pressure is reduced substantially to the cut-out point of the controller. This provides for reducing a cycling of the compressor between low and high speeds to a minimum.

Inasmuch as the pointers 66 and 71 are located in the common slot 67, these pointers cannot be adjusted in a manner to mix up the positions of the various contacts. This prevents any possibility of the device being adjusted in an improper manner with reference to the control sequence.

From the foregoing it will be apparent that this invention provides a control arrangement for a refrigeration system which varies the speed or capacity of the compressor or other actuating means for the refrigeration system in accordance with the load on the system. It will also be apparent that this arrangement causes the compressor to cycle between off and low speed for light load conditions while causing the compressor to cycle between low speed and high speed for heavier load conditions. It will be seen that provision is made for readily and independently adjusting the various cut-in and cut-out points thereby rendering the control system readily applicable to different refrigerants and also permitting ready adjustment of a given installation so as to provide the desired results. While for illustrative purposes, the invention has been illustrated as applied to a refrigeration system having a thermostatically controlled fan, it will be understood that this control system is of general application and may be utilized in air conditioning work as well as a refrigeration system. Inasmuch as many modifications which are within the scope of my invention may occur to those skilled in the art. I desire to be limited only by the scope of the appended claims.

50 I claim as my invention:

1. In a refrigeration system, in combination, variable capacity actuating means for said system, a movable device positioned in accordance with pressure within said refrigeration system which tends to vary upon variations in the load on the system, control means associated with said actuating means for varying the capacity of said actuating means in steps, a first control device actuated by said movable device, connections between said first control device and said control means for rendering said control device capable of initiating operation of said actuating means, said first control device being incapable of placing said actuating means out of operation, a second control device also actuated by said movable device for placing said actuating means out of operation, a third control device actuated by said movable device and connected to said control means for changing the capacity of said actuating means from a low value to a high value, said third control device being incapable of changing said capacity from a high value to a low value, and a fourth control device actuated by said movable device and connected to said control means for changing the capacity of said

actuating means from said high value to a low value.

2. In the refrigeration system, in combination, variable capacity actuating means for said system, a movable device positioned in accordance with pressure within said refrigeration system which tends to vary upon variation in the load on the system, control means associated with said actuating means for varying the capacity of said actuating means in steps, a first control device 10 actuated by said movable device, connections between said first control device and said control means for rendering said control device capable of initiating operation of said actuating means, said first control device being incapable of placing said actuating means out of operation, a second control device also actuated by said movable device for placing said actuating means out of operation, a third control device actuated by said movable device and connected to said control 20 means for changing the capacity of said actuating means from a low value to a high value, said third control device being incapable of changing said capacity from a high value to a low value, a fourth control device actuated by 25 said movable device and connected to said control means for changing the capacity of said actuating means from said high value to a low value, and means for independently adjusting the relationship between said first, second, third and 30 fourth control devices and said movable device.

3. In a refrigeration system, in combination, variable capacity actuating means for said system, a movable device positioned in accordance with pressure within said refrigeration system 35 which tends to vary upon variation in the load on the system, control means associated with said actuating means for varying the capacity of said actuating means in steps, a first control device actuated by said movable device, connections between said first control device and said control means for rendering said control device capable of initiating operation of said actuating means, said first control device being incapable of placing said actuating means out of operation, a second control device also actuated by said movable device for placing said actuating means out of operation, a third control device actuated by said movable device and connected to said control 40 means for changing the capacity of said actuating means from a low value to a high value, said third control device being incapable of changing said capacity from a high value to a low value, a fourth control device actuated by 45 said movable device and connected to said control means for changing the capacity of said actuating means from said high value to a low value, and means for independently adjusting at least a pair of said control devices, and means associated with said adjusting means to prevent adjustment of said control devices in a manner causing improper control sequence.

4. In a refrigerating system, in combination, variable capacity actuating means for said system, control means associated with said actuating 55 means for varying the capacity of said actuating means in steps, said control means including a first relay and a second relay, a movable device positioned in accordance with pressure within said refrigeration system which tends to vary 60 upon variation in the load on the system, a first contact means actuated by said movable device and connected to said first relay for actuating said relay in one direction, said first contact means being incapable of actuating said first re- 65

lay in the opposite direction, a second contact means actuated sequentially with respect to said first contact means by said movable device, said second contact means being connected to said first relay for causing movement of said relay in said opposite direction, a third contact means actuated by said movable device and connected to said second relay for causing movement thereof in a predetermined direction, said third contact means being incapable of causing movement of said second relay in said opposite direction, and a fourth contact means actuated sequentially by said movable device and connected to said second relay for causing movement of said second relay in said opposite direction.

5 5. In a refrigeration system, in combination, variable capacity actuating means for said system, control means associated with said actuating means for varying the capacity of said actuating means in steps, said control means including a first relay and a second relay, a movable device positioned in accordance with pressure within said refrigeration system which tends to vary upon variation in the load on the system, a 10 first contact means actuated by said movable device and connected to said first relay for actuating said relay in one direction, said first contact means being incapable of actuating said first relay in the opposite direction, a second contact means actuated sequentially with respect to said first contact means by said movable device, said second contact means being connected to said first relay for causing movement of said relay in said opposite direction, a third contact 15 means actuated by said movable device and connected to said second relay for causing movement thereby in a predetermined direction, said third contact means being incapable of causing movement of said second relay in said opposite direction, a fourth contact means actuated sequentially by said movable device and connected to said second relay for causing movement of said second relay in said opposite direction.

20

25

30

35

ly by said movable device and connected to said second relay for causing movement of said second relay in said opposite direction, and means for independently adjusting the relationship between said contact means and said movable member. 5

6. In a refrigeration system, in combination, variable capacity actuating means for said system, control means associated with said actuating means for varying the capacity of said actuating means in steps, said control means including a first relay and a second relay, a movable device positioned in accordance with pressure within said refrigeration system which tends to vary upon variation in the load on the system, a first contact means actuated by said movable device and connected to said first relay for actuating said relay in one direction, said first contact means being incapable of actuating said first relay in the opposite direction, a second contact means actuated sequentially with respect to said first contact means by said movable device, said second contact means being connected to said first relay for causing movement of said relay in said opposite direction, a third contact means actuated by said movable device and connected to said second relay for causing movement thereof in a predetermined direction, said third contact means being incapable of causing movement of said second relay in said opposite direction, a fourth contact means actuated sequentially by said movable device and connected to said second relay for causing movement of said second relay in said opposite direction, means for independently adjusting the relationship between said contact means and said movable member, and means associated with said adjusting means to prevent adjustment in a manner causing improper control sequence. 35

WILLIAM L. McGRATH. 40
